COMBINED MUSIC HOLDER AND GUITAR STAND

Rolando Valdes Blain, 72 Barrow St.,
New York, N.Y. 10014

Filed Mar. 29, 1971, Ser. No. 129,311

Term of patent 14 years

Int. Cl. D6—99

U.S. Cl. D6—18

FIG. 1 is a front perspective view of a combined music holder and guitar stand showing my design;

FIG. 2 is a side elevational view thereof; and

FIG. 3 is a rear elevational view thereof.

I claim:

The ornamental design for a combined music holder and guitar stand, as shown.
